UNITED STATES PATENT OFFICE.

OTTO F. FOGELSTRAND, OF WESTFIELD, MASSACHUSETTS, ASSIGNOR TO
THE TEXTILE MANUFACTURING COMPANY, OF SAME PLACE.

DESIGN FOR AN EAR FOR CASKET-HANDLES.

SPECIFICATION forming part of Design No. 16,465, dated January 12, 1886.

Application filed June 10, 1885. Serial No. 168,242. Term of patent 7 years.

To all whom it may concern:

Be it known that I, OTTO F. FOGELSTRAND, a citizen of the United States, residing at Westfield, in the county of Hampden and State of Massachusetts, have invented and produced a new and original Design for an Ear or Bracket for Casket-Handles, of which the following is a specification, reference being had to the accompanying drawing, forming part thereof, in which the only figure is a front elevation of my newly-designed ear.

A designates the base plate, and B the ear proper, which projects forward from the central portion of the plate A. The contour of the base plate is composed of curved and straight lines, as clearly shown. The edge *a* is beveled so as to give the appearance of a plain band, as viewed in front elevation. Just inside of the beveled edge is an ornamental border or band of the same general form as the contour of the plate A. Surrounding the base of the ear B, and upon the face of the plate A, is a border or band composed, mainly, of lattice-work and forming a six-sided figure. At each angle of this lattice-work, border, or band there is a small ornament, as shown. The space between the lattice-work, border, or band and the border near the edge of the plate A is ornamented with scroll-work, which radiates from the central portion, as shown.

I claim—

1. The design for an ear of a casket-handle herein shown and described, the same consisting of the ear and base-plate, the latter having a contour which, when viewed from the

front, as in the accompanying drawing, is substantially of a rectangular form, the upper and lower edges of which are composed, mainly, of a series of intersecting curved lines, while the two vertical edges are composed of intersecting straight lines, excepting at near their junction with the upper and lower edges, where they curve outwardly and meet in a point at the several corners of the base, substantially as shown.

2. The design for an ear of a casket-handle herein shown and described, the same consisting of the ear having the hexagonal base, and the base-plate having an edge composed of intersecting curved and straight lines in the form shown, and the ornamentation between said edge and base of the ear.

3. The design for an ear of a casket-handle herein shown and described, the same consisting of the ear and base, the latter having the contour shown, the beveled edge, and ornamental border within the edge, of the same general form as the contour of the base.

4. The design for an ear of a casket-handle herein shown and described, the same consisting of the ear having at its base a hexagonal form, and the base-plate having an ornamental border of corresponding form around the base of the ear, and the ornamental scroll-work radiating from the sides and corners of said hexagonal border.

OTTO F. FOGELSTRAND.
